UNITED STATES PATENT OFFICE.

RICHARD SCHOFIELD, OF PARIS, ONTARIO, CANADA, ASSIGNOR TO JOHN PENMAN, OF SAME PLACE.

ART OF KNITTING STOCKINGS.

SPECIFICATION forming part of Letters Patent No. 288,186, dated November 6, 1883.

Application filed April 5, 1883. (No model.)

To all whom it may concern:

Be it known that I, RICHARD SCHOFIELD, of the town of Paris, in the county of Brant, in the Province of Ontario, Dominion of Canada, have invented certain new and useful Improvements in the Art of Knitting Stockings, of which the following is a specification.

The object of the invention is to produce by a knitting-machine a stocking having a plain foot and a ribbed leg without exhibiting any flaw at the connection between the plain and ribbed work; and it consists, essentially, in the method hereinafter more fully described, and then pointed out in the claim.

15 It will be found that in attempting to add a ribbed leg to a plain foot by operating an ordinary circular-knitting machine in the usual manner a series of holes will be formed around the stocking at the point where the rib joins the plain work; and it is to obviate this defect that my improvement in the art of manufacturing machine-knitted stockings has been made, which improvement I shall now proceed further to describe with the aid of the 20 accompanying drawing, which shows an enlarged view of a section of a stocking at the point where the ribbing joins the plain work.

In said drawing, A A represent two of the dial-needles; B B, the cylinder-needles; C C, the holes usually left when an attempt is made to add a ribbed leg to a plain foot by operating an ordinary circular-knitting machine in the usual manner, and D D D the loop by which such holes are closed when my method of operation is pursued.

35 My mode of operation is as follows: Having knitted a plain foot on any suitable machine, I transfer the said foot onto the cylinder-needles (represented by B) of an ordinary 40 circular-knitting machine, but which circular-knitting machine must be provided with a dial having adjustable ribbing-needles, (represented by A.) so that the said ribbing-needles may easily be thrown in and out of work.

45 Having transferred the plain foot onto the cylinder-needles B, I turn the machine so as to knit a single round of stitches accomplished by the cylinder-needles alone. This single row of stitches, however, is not essential, and may be omitted without changing the spirit of my invention. I then throw the

ribbing-needles A into action and cause the combined cylinder and ribbing needles to knit the next round of stitches, when I once more throw the ribbing-needles A out of action and cause the cylinder-needles B to produce another single round of stitches, when the ribbing-needles are again thrown into action and the rib-work proceeded with until the leg of the stocking has been completed.

55 It will of course be understood that more than a single round of stitches by the cylinder-needles alone when they first enter the plain work might be made without affecting the principle of my invention; but in order to 60 make a perfect job it is not advisable to make more than a single round of stitches with the cylinder-needles alone between the point where the ribbing-needles are first thrown into action and the point where they are thrown 65 into action for the purpose of continuing the rib-work; nor can more than one round of stitches with the combined needles be made when the ribbing-needles are first thrown into the work, as in such a case holes, as shown at 70 C, will appear round the stocking, made by the action of the ribbing-needles when they first take hold of the stitches, these holes in my process being closed by the loops D, formed by the cylinder-needles, as before stated, between 75 the point where the ribbing-needles are first brought into action and the point where they are thrown into action for the purpose of continuing the ribbed work.

80 In conclusion, I should mention that in the event of the combined total of the ribbing and cylinder needles being equal to the number of stitches in the foot at the point where the joint is made, a perfect connection would of course be formed; but the leg thus made would be 85 too narrow and the stocking would therefore not be properly shaped. My invention does not relate to the manufacture of an imperfect stocking, but solely to an improvement in the art of producing a perfect stocking having a 90 plain foot and a ribbed leg, and in which a greater number of stitches are made around the leg than around the foot at the point where the joint is formed.

95 What I claim as my invention is—
100 The improvement in the art of knitting stockings which consists in first knitting a

plain foot, then transferring said foot to the cylinder-needles of a circular-knitting machine adapted to knit plain and ribbed work, then throwing the dial or ribbing needles into 5 operation and knitting a round of stitches on both cylinder and dial needles, then throwing the dial-needles out of operation and knitting one or more rounds of stitches on the cyl-

inder-needles alone, then bringing the dial-needles into operation again, and completing to the knitting of the stocking on both cylinder and dial needles, substantially as described.

RICHARD SCHOFIELD.
